BOOT TREE FOR RIDING AND LIKE BOOTS

Joseph Edward Hyams, Edgbaston, Birmingham, England, assignor to Vic-Tree Products (Birmingham) Limited, Birmingham, England, a British company

Filed Mar. 8, 1963, Ser. No. 263,895

Claims priority, application Great Britain, Mar. 17, 1962, 10,309/62

2 Claims. (Cl. 12—114.6)

The present invention has relation to a boot tree for riding and like boots of the type wherein two substantially semi-cylindrical inwardly facing shaping members are operatively connected so that they can be placed in the leg of the boot and subsequently opened outwardly to hold the boot in shape and be contracted when desired for removal.

The present invention has for its object a simple and efficient tree of the type aforesaid requiring little effort for its operation.

According to the present invention there is provided a boot tree for riding and like boots comprising two substantially semi-cylindrical inwardly facing shaping members individually connected to the lower extremities of a scissor-like operating member the upper extremities of which operatively protrude beyond the extremities of the same shaping members, spring means being incorporated for normally forcing the shaping members apart.

In operation the shaping members are contracted by the manual operation of the upper extremities of the scissors against the action of the spring and are then placed in the leg of the boot and the said members allowed to be forced apart to shape the leg by virtue of the spring. A closing movement of the operative part of the scissors closes the shaping members and enables them to be readily withdrawn. A finger operable catch which may be in the form of an automatic gravity catch is preferably employed so as to secure the finger operable upper extremities of the scissors with the shaping members in the closed position.

In order that the invention may be clearly understood and readily carried into practice reference may be had to the accompanying explanatory drawings in which:

FIG. 1 is a part sectional elevation of the boot tree in the contracted or out of use condition.

FIG. 2 illustrates the boot tree in the expanded or open condition for shaping the jack boot, and

FIG. 3 is a transverse sectional elevation taken on line 3—3 of FIG. 1.

In an embodiment of the present invention two shaping members *a* are not strictly semi-cylindrical but taper slightly from top to bottom, as illustrated. Attached to the inner facing of each of the said shaping members substantially centrally is a bracket with two lugs *a*¹ to which the lower extremity *b*¹ in each instance of the scissor-like operating member *b* is attached and the arms of said member may be of inwardly facing channel section and they may accommodate a closely wound coil spring *c* of arch formation the extremities of which are attached to lugs *b*² on the member *b*, the spring tending to move the shaping members *a* apart. The

2

upper extremities *b*³ of the scissor-like operating member *b* are advantageously of outwardly facing channel section, the extreme ends being of outwardly facing hook formation *b*⁴ to form finger pieces. Pivoted to one upper part is a catch member *d* which operates in a slot in the other handle part, said catch member having two notch members *d*¹, *d*² for locating the scissor-like operating member *b* with the handles closed, FIG. 1, and the shaping members in adjacency or, alternatively, locating the tree with the handles open, FIG. 2, and the shaping members *a* spaced apart the catch *d* being advantageously of a gravity character, and having a finger manipulative parts so that two fingers can engage *b*⁴ and one finger disengaged from *b*⁴ when desired to engage *d*³.

In use the scissor-like operating member is closed by hand to allow the catch *d* to gravitate to lock the device in the closed position, FIG. 1, and the shaping members now in adjacency are introduced into the leg of the boot. The catch is released by a finger engaging *d*³ so that the shaping members *a* are forced apart by the spring *c* to bear against the leg to hold it in shape. When it is desired to remove the tree the handles *b*⁴ of the scissor-like member *b* are closed, the gravity catch falling so that notch *d*¹ comes into operation, in which position the shaping members are in adjacency and can be readily slid from the leg of the boot. *e* represents springs introduced between pivot pins *a*² and the limbs of the member *b* and these springs *e* not only tend to close the device but properly locate the members *a* in relation to the limbs of the member *b*.

I claim:

1. A boot tree for riding and like boots comprising, in combination, a pair of substantially semi-cylindrical inwardly facing shaping members, a scissors-like operating member having a pair of upper and a pair of lower extremities, pivotal connection between the lower extremities of the scissors-like member and each shaping member, spring means in said scissors-like member tending to separate said shaping members, said spring means comprising a coil spring attached to the lower extremities of said member and positioned in inwardly facing channel shaped parts of said member, and a two step pivotal catch mounted on one of said upper extremities of the scissors-like member and adapted to engage a portion of the other of said pair of upper extremities for limiting the separation of said shaping members.

2. A boot tree according to claim 1 having springs engaging said scissors-like member and said shaping members for resiliently limiting pivotal movement of the shaping members on said pivotal connections.
